[57] CLAIM

The ornamental design for a fire-place, as shown and described.

DESCRIPTION

FIG. 1 is a front elevational view of a fire-place, showing my new design;

FIG. 2 is a top plan view thereof;

FIG. 3 is a side elevational view, the opposite side being a mirror image thereof;

FIG. 4 is a rear elevational view thereof;

FIG. 5 is a bottom plan view thereof;

FIG. 6 is a front elevational view of the fire-place with the front doors fully opened;

FIG. 7 is a front elevational view of the fire-place with the front doors partially opened.
